UNITED STATES PATENT OFFICE.

EVELINA P. SMITH, OF CHICAGO, ILLINOIS.

COUCH.

1,339,608.

Specification of Letters Patent. Patented May 11, 1920.

Application filed February 13, 1919. Serial No. 276,813.

To all whom it may concern:

Be it known that I, EVELINA P. SMITH, a citizen of the United States, and a resident of the city of Chicago, in the county 5 of Cook and State of Illinois, have invented certain new and useful Improvements in Couches; and I do hereby declare that the following is a full, clear, and exact description of the same, reference being had to the 10 accompanying drawings, and to the numerals of reference marked thereon, which form a part of this specification.

This invention relates to couches, more particularly couches of the type in which a 15 mattress and springs are supported by a wooden frame.

In couches of this type as commonly constructed the mattress has been connected to the springs or to the frame in such a way 20 that it cannot be readily detached and also, even when detached the mattress is usually constructed so that its position on the couch could be reversed if so desired. Further in couches of this type the space beneath 25 the springs has been wasted and in addition no means have been provided for preventing any dirt from the springs or the mattress from falling down onto anything which might be underneath.

My invention is particularly designed to 30 overcome these objections.

It is an object therefore of my invention to provide a couch in which the mattress is readily separable from the frame and springs 35 and so constructed that its position relative thereto may be reversed.

A further object of the invention is to produce a collapsible couch which can be readily taken apart and erected while still 40 having the desired stability and rigidity when assembled.

An important object of my invention is to provide a couch having a drawer or receptacle in its lower portion.

It is also an object of my invention to 45 provide means whereby any dirt which may accumulate around the mattress, springs or other parts is prevented from entering the drawer or other receptacle which is located 50 thereunder.

Other and further important objects of this invention will be apparent from the disclosures in the specification and drawings.

The invention in a preferred form is illustrated in the drawings and hereinafter more 55 fully described.

On the drawings:

Fig. 1 is a side elevation of a couch embodying my invention.

Fig. 2 is a plan view of the same.

Fig. 3, is a section on the line 3—3, of Fig. 1 with parts broken away to disclose the underlying construction.

Fig. 4 is a section on the line 4—4, of Fig. 1.

Fig. 5 is a side elevation of the drawer and frame detached and arranged for crating.

Fig. 6 is a section on the line 6—6, of Fig. 2.

Fig. 7, is a perspective view of one corner of the frame, after disconnecting the side and end members.

Fig. 8 is a section on the line 8—8, of Fig. 2.

Fig. 9 is a plan view of one part of the frame.

As shown on the drawings:

The couch comprises a frame generally designated as 10, carrying a mattress 11, resiliently supported by springs 14, which are in turn carried by a series of transverse slats 15. The ends of these slats rest on shoulders 16, in the form of wooden strips nailed or otherwise secured to the frame 10. Underneath the slats 15, is slidably arranged a drawer 17.

The frame 10, comprises end members 12, rigidly secured to end posts 19, to the lower ends of which may be attached casters 90 28. The side members 13, are detachably connected to the end posts in any suitable way so that the frame may be taken apart for shipment.

The connection of the side members to 95 the end posts may conveniently be carried out by providing pins 20, projecting from the ends of the side members 13. These pins 20, are provided with enlarged heads for detachable locking engagement with a metal plate 18, secured to the end posts 19. These metal plates are formed with slots 21, the upper parts of which are large enough to allow the passage of the heads of the pins 20, so that the latter may be inserted and 100 then moved downward in the slot so as to

bring the heads of the pins into engagement with the narrower lower portions of said slots.

The mattress itself may be of any suitable construction and may be stuffed with horse hair or other material. Preferably, it is rectangular in cross section so that it may lie on the springs with either side uppermost. For this purpose the mattress should 5 preferably be flat both top and bottom. It is further desirable that the mattress be able to slide up and down between the frame members while in use, and for this reason the mattress should have substantially perpendicular edges.

It is important that if the couch be used as a settee as distinguished from a bed that at least one of the sides of the couch be sufficiently below the top of the mattress that 10 the occupant's legs will never come in contact with the upper edge of that side when the mattress and the springs are pressed downward under such individual's weight. Accordingly the height of the sides, the 15 thickness of the mattress and the strength of the springs must be adjusted so that on the one hand when the springs are fully extended all of the sides of the frame will extend above the lower margin of the mattress in order to hold the latter in position 20 and on the other hand at least one side will not extend above the upper margin of the mattress when the maximum weight which the couch is designed to carry is placed 25 thereon.

In order to keep the mattress clean, a closely fitting removable cap cover 29, of any desired ornamental material is provided. By this means it will be possible to reverse 30 the position of the mattress on the springs without marring the ornamental covering of the couch through contact with the springs or with the frame carrying the same. When the couch is used as a bed, the 35 cap also enables the bed to be made in the morning and then covered by the cap during the day for use as a settee.

The springs 14, may be of any convenient construction it merely being necessary that 40 the springs be held together in spaced relation when the couch is taken apart in order that the parts may be easily re-assembled.

In order to prevent lateral displacement of the slats and also at the same time to 45 prevent spreading or warping of the side members 13 of the frame dowel pins, 22, are provided on each of the shoulders 16, for engagement with corresponding apertures in the slats 15.

Considerable dirt will unavoidably enter the space between the sides of the mattress and the frame of the couch and unless this is collected in some way it will eventually find its way into the drawer 17. In order to catch this dirt I provide a removable apron 25, preferably arranged between the slats and the springs. This apron may be of canvas or other suitable durable material. For retaining it in position the apron may conveniently be provided with eyelets 26, adapted for engagement with turnbuttons 27, mounted on ends of the slats. With this construction the apron is always held in place but still can be readily detached for cleaning purposes when dirt has accumulated thereon.

In order to accommodate the drawer 17, the lower parts of the side members 13, are cut away so that in closed position the front and rear parts of the drawer form a continuation of the side members of the frame. This drawer 17, is supported entirely by the end members 12, of the frame which are provided for this purpose with an inwardly projecting shoulder 31, on which the side edges or margins of the drawer may rest.

Further, as it is desirable to prevent tilting of the drawer when partially withdrawn a tongue 23, is arranged along each side of the drawer for sliding engagement with a corresponding groove 24 on the adjacent end member 12, as shown more particularly in Fig. 6.

I am aware that numerous details of construction may be varied through a wide range without departing from the principles of my invention and I therefore do not purpose limiting the patent granted otherwise than necessitated by the prior art.

I claim as my invention:

A device of the kind described comprising a collapsible frame having end members and side members detachably secured thereto, springs within the frame, a mattress supported by the springs, means detachably carried by the side members adapted to support the springs and prevent spreading of the side members, and a drawer slidably supported by said frame having front and rear walls forming downward continuations of said side members.

In testimony whereof I have hereunto subscribed my name in the presence of two subscribing witnesses.

EVELINA P. SMITH.
